UNITED STATES PATENT OFFICE.

EMBURY MCLEAN, OF BROOKLYN, NEW YORK, ASSIGNOR TO THE ENGINEER COMPANY, OF NEW YORK, N. Y., A CORPORATION OF NEW YORK.

CONTROL FOR FURNACES.

Application filed September 10, 1923. Serial No. 661,760.

My invention more particularly relates to the control for a furnace to which fluid fuel is supplied.

My invention will best be understood by reference to the accompanying drawings in which I have illustrated the preferred form of apparatus for carrying out my invention, and in which Fig. 1 is a diagrammatic side view, partially in section, of a boiler and its furnace, together with the control therefor; Fig. 2 is an enlarged side view of certain parts shown in Fig. 1 and partially in section to illustrate a valve structure; Fig. 3 is a sectional view through the control device operated by the fluid fuel; Fig. 4 is a plan view, on a smaller scale, of the lower portion or half of the device shown in Fig. 3; Fig. 5 is a top plan view, partly in section, of the upper portion or half of the device shown in Fig. 3; Fig. 6 is a side view partially in section similar to Fig. 1 illustrating a modification of my invention, and Fig. 7 is a view similar to Fig. 1 illustrating a further modification.

I have illustrated my invention in connection with a steam boiler 10, although it is to be understood that by invention is not limited to this particular use. The boiler is fired by a furnace, indicated, generally, at 11, provided with a horizontal perforated partition 12 and a combustion chamber 13. The air to the furnace may be controlled by a damper 14, which may be operated in any desired manner. I have illustrated at 15 a balanced draft device, the construction and operation of which may be the same as that shown in my Patent No. 1,355,157, October 12, 1920, and need not further be described. Briefly it may be stated that the balanced draft device is operated by furnace pressure and controls the position of the damper 16 in the outlet flue 17 of the boiler.

The means for supplying fluid fuel to the furnace comprises a burner or nozzle 18 located preferably in the front portion of the furnace above the horizontal partition 12. This burner or nozzle may be of any well-known type for feeding fluid fuel in a mixture with an atomizing element, such as steam or air to the furnace chamber. Oil or other fluid fuel is fed to said burner from a pump 19 through a pipe 20, a rate-of-flow device, indicated, generally, at 21 and a pipe 22. A valve member 23 is interposed in the pipe 20, the valve being op-

erated by an arm 24 through a cam member 25, which is actuated by an attached drum or disc on which is wound a chain 26 passing over a pulley 27 and attached to the piston rod 28 of a device, indicated, generally, at 29, for controlling the rate of feed of the fuel, and here shown as a "Mason compensating steam regulator" operating in accordance with boiler pressure, and the construction and operation of which is well known to those skilled in the art and need not here be more fully described. It will be understood that the flow of fuel to the furnace may be controlled in any desired manner.

An atomizing fluid, here shown as steam, is supplied to the burner 18 by means of a pipe 30, which is connected to the boiler. A regulating pressure valve 31 is preferably interposed in the pipe 30 for producing substantially constant pressure in the steam supplied to the steam atomizing control valve hereinafter described. The construction and operation of this regulating pressure valve is well understood and need not further be described.

In accordance with my invention, the supply of atomizing fluid is controlled by a characteristic of the flow of fluid fuel to the burner, and preferably by the rate of flow thereof. The rate-of-flow device 21 comprises a casing, the lower half of which is indicated at 32, and the upper half of which is indicated at 33, said members being connected by heated bolts 34 having nuts thereon, the casing forming a diaphragm chamber, a flexible diaphragm 35 being clamped between the upper and lower sections of the casing and shutting off communication between the upper portion of the chamber and the lower portion of the chamber, except as hereinafter described. Integral with the lower half of the casing 32 is an inlet connection 36 having a port 37 leading to an opening 38 through the flange of the member 32 and leading into a passage 39 in the wall of the member 33, said passage 39 communicating with the space in said member 33 above the diaphragm 35. The connection 36 is made with that portion of the pipe 20 nearest to and leading from the pump 19. Connected to the lower member 32 is an outlet connection 40 opening into the lower chamber of the regulating device below the diaphragm 35, said connection 40

being connected to that part of the pipe 22 leading from the regulator to the burner 18. The chamber in the upper half 33 of the casing above the diaphragm 35 opens 5 through a port 41 into a valve casing 42, preferably formed integral with the member 33 and containing a tapered turn-plug valve 43, the latter having a port 44 adapted to communicate with the said port 41 and 10 leading to the internal bore 45 of the valve, which, in turn, communicates with a passage 46 leading into the chamber beneath the diaphragm 35. In order to provide for a tight fit, the valve 43 is preferably tapered and fitted to a correspondingly tapered bore in the casing 42 and is forced 15 toward its seat by a spring 47 surrounding a stem 48 of said valve, and at one end abutting a packing gland 49 threaded into the casing 42, and its other end abutting the upper end of said valve 43. The valve is 20 provided with a head 50 adapted to be engaged by a wrench or other suitable means by which it may be rotated. Connected to 25 the diaphragm 35, in any suitable manner, as at 51, is one end 52 of a rod 53 extending upward through a stuffing box 54 in the upper wall of the member 33, the upper end of said rod 53 being loosely pivoted, as at 30 55, to a lever 56, one end of which is pivoted, as at 57, to the member 33, and the other end of which is connected to a flexible member 58, shown as a chain, passing 35 upward over a pulley 59 on a shaft 60, the opposite end of the chain preferably being provided with a counterweight 61. The means for connecting the rod 53 to the diaphragm preferably consists of a dished plate 62 having a flange 63 secured by a fluid 40 tight joint to the lower face of the diaphragm by means of screws 64 extending through said flange, packing washers 65 being interposed between the flange of the dished plate and the diaphragm, the screws 45 being threaded into a washer or ring 66 on the upper side of the diaphragm. The dished portion of the plate 62 extends upward through a central opening in the diaphragm and has a central opening 67 50 through which the rod 53 extends, the rod having beneath said plate an enlargement or head 68 of greater diameter than the opening in said plate. The underside of the dished plate 62 is closed against leakage by a plate 69 held in place by the screws 64. On the casing of the regulator is a bracket 70 between which and the lever 56 55 is suitably supported and held a compression spring 71 tending to move the lever 56 upwardly. One end of the spring 71 is seated in a spring seat 72 supported on one end of an adjusting screw 73 threaded through the bracket 70 and by means of which the resistance of the spring 71 to the downward 60 movement of the lever 56 may be regulated.

The screw 73 may be locked in adjusted position by a jam nut 74 threaded thereon. The upper end of the spring 71 surrounds a lug 75 which is preferably formed on the lower side of the lever arm 56.

The operation of the rate-of-flow device is as follows: The fluid fuel enters the connection 36 and flows through ports 37 and 39 into the space above the diaphragm 35, thence through the port 41 and valve port 44 and port or passage 46 into the space beneath the diaphragm 35, from which space it flows outward through the pipe 22 to the burner 18. The valve 43 is operable to cause a restriction to the flow of fluid fuel between the upper and lower chambers of the regulator having a diaphragm between them, so as to create a reduction in pressure in the chamber beneath the diaphragm, this reduction in pressure being employed to cause movement of the diaphragm in accordance with the rate of flow of fluid fuel to operate the lever 56, so as to control the rate of flow of atomizing fluid in accordance with the rate of flow of fluid fuel, as will be more fully hereinafter described. It will be understood that the valve 43 is set so as to result in a restriction, giving the desired difference in pressure between the fluid in the two chambers, and any variations in this difference of pressure due to fluctuations in the rate of flow during the operation of the furnace, will operate the diaphragm to correspondingly regulate the position of the arm 56. The chambers on opposite sides of the diaphragm 35 are preferably designed so as to be of equal volume and symmetrical in shape, so that the effect of the velocity head of the fluid flowing through the two chambers will not tend to move the diaphragm, any action of the velocity head on one side of the diaphragm being counterbalanced by a similar action on the other side. The result of the neutralizing or counterbalancing of the pressures in the two chambers is that the diaphragm is actuated by the difference in total pressure due to the restriction of the passage between the two chambers. The movement of the arm 56 through the variations in the rate of flow of fluid fuel through the regulating device 21 operates the pulley 59 to which is attached a cam member 76 preferably provided with a plurality of radial slots 77, in which are secured bolts 78 progressively removed from the center in the successive slots, so as to form a spiral on which rests an arm 79 weighted as at 80, the arm 79 operating a valve 81 located in the pipe 30 which supplies atomizing fluid to the burner, the construction and operation being such that as the rate of flow of fluid fuel to the furnace increases or decreases, the valve 81 is actuated to correspondingly increase or decrease the supply of atomizing fluid to the

burner. It will be understood that the bolts 78 in the slots 77 may be so adjusted that the rate of supply of the atomizing fluid may bear any desired relation to any rate of supply of the fluid to the burner.

The valve 23 which controls the flow of fluid fuel to the regulating device may be of any suitable form. In the device illustrated in Fig. 2, the valve member 82 is in the form of a hollow shell and comprises two plates 82^a and 82^b connected by guide members 82^c which are received in openings 83 and 83^a in a partition member 84, preferably formed integral with the connecting member 85. The valve member 82 is connected by a stem 86 to the inner end of the arm 24, as at 87, the arm being pivoted at 88 in the valve casing. The arm 24 is actuated by the cam member 25 which may be of the same form as the cam member 76 and need not be more fully described, it being understood that the cam member 25 is actuated by a pulley on which is wound the chain 26.

25 In the modified arrangement illustrated in Fig. 6, not only is the supply of atomizing fluid controlled in accordance with a characteristic of the flow of fluid fuel to the burner, but the supply of air to the 30 furnace is also controlled in accordance with a characteristic of the flow of fluid fuel. In the arrangement illustrated the arm 56, which is actuated in accordance with a characteristic of the flow of fluid fuel, and 35 specifically in accordance with the rate of flow of fluid fuel, actuates not only the valve 81, which controls the supply of atomizing fluid to the burner, but is connected by means of a chain 89, after passing over pulleys 90 and 91, to a weighted arm 92 on a shaft 93 on which is mounted a damper 94 in an opening 95 in the wall of the setting, through which air is supplied to the space beneath the partition 12 and through the 40 openings in the partition to the furnace. The arm 56, therefore, the movement of which is in accordance with the rate of flow of fluid fuel to the burner, controls not only the supply of atomizing fluid, but 45 controls the supply of air to the furnace, so that the amount of air supplied is in accordance with the amount of fluid supply.

In the arrangement illustrated in Fig. 7, the arm 56, which controls the supply of 50 atomizing fluid, also adjusts the position of the balanced draft device 15, the movement of which, in turn, controls the damper 16 in the outlet flue to control the gases passing through the boiler and furnace. The arm 56 is connected by a chain 96, which passes 55 over pulleys 97 and 98 to an arm on the lower part of the balanced draft plate in the balanced draft device 15, through a spring 99. The construction and operation 60 of the spring connection between the chain

and the plate included in the balanced draft device 15 is or may be the same as that which is fully shown and described in my application Serial No. 521,318, which was filed in the Patent Office on or about December 10, 1921, and patented March 16, 1926, No. 1,576,754, to which reference may be made for fuller details as to the construction and operation. In the device illustrated in Fig. 7, therefore, not only is the supply of atomizing fluid controlled in accordance with the rate of flow of fluid fuel, but the position of the balanced draft regulator is also adjusted in accordance with the rate of flow of fluid fuel, and correspondingly the opening in the outlet flue is varied so that the rate of flow of gases through the boiler and furnace is in accordance with the rate of supply of fluid fuel to the burner.

I claim:

1. The method of operating a furnace for which fluid fuel is atomized by a fluid, which consists in controlling the supply of atomizing fluid in response to variations in the rate of flow of fluid fuel to the furnace.

2. The method of operating a furnace for which fluid fuel is atomized by a fluid, which consists in supplying the atomizing fluid at a constant pressure, and controlling the rate of supply thereof to the furnace in accordance with the rate of fuel supply.

3. In a furnace, means for supplying fluid fuel to the furnace, means for atomizing the fluid fuel with a fluid, means for controlling the rate of supply of atomizing fluid in response to variations in the rate of supply of fluid fuel.

4. In a furnace, means for supplying fluid fuel to the furnace, means for atomizing the fluid fuel with a fluid, and means for controlling the rate of supply of atomizing fluid in response to variations in the rate of flow of fluid fuel.

5. In a furnace, means for supplying fluid fuel to the furnace, means for atomizing the fluid fuel with a fluid, and means for controlling the rate of supply of atomizing fluid in response to variations in the rate of supply of fluid fuel and means for varying the ratio of the rate of supply of atomizing agent to the rate of flow of fluid fuel.

6. In a furnace, means for supplying fluid fuel to the furnace, a source of atomizing fluid under variable pressure, means for supplying the atomizing fluid at a substantially constant pressure, and means for controlling the rate of supply of atomizing fluid in accordance with the rate of supply of fluid fuel.

7. In a furnace, means for supplying fluid fuel to the furnace, a source of atomizing fluid under variable pressure, means for supplying the atomizing fluid at a substantially constant pressure, and means for controlling the rate of supply of atomizing

fluid in accordance with the rate of supply of fluid fuel and means for varying the ratio of the rate of supply of atomizing fluid to the rate of supply of fluid fuel.

5 8. In a steam boiler and its furnace, means for supplying fluid fuel to the furnace, means for supplying steam from the boiler for atomizing the fluid fuel, and means for controlling the rate of supply of 10 atomizing fluid in response to variations in the rate of supply of fluid fuel.

9. In a steam boiler and its furnace, means for supplying fluid fuel to the furnace, means for supplying steam from the 15 boiler at substantially constant pressure for atomizing the fluid fuel, and means for controlling the rate of supply of atomizing fluid in accordance with the rate of supply of fluid fuel.

20 10. In a furnace, means for supplying fluid fuel to the furnace, means for supplying air to the furnace, means for atomizing the fluid fuel with a fluid, and means for controlling the rate of supply of atomizing 25 fluid and of air in response to variations in a characteristic of the flow of fluid fuel.

11. In a furnace, means for supplying fluid fuel to the furnace, means for supplying air to the furnace, means for atomizing 30 the fluid fuel with a fluid, and means for

controlling the rate of supply of atomizing fluid and of air in accordance with the rate of fuel supply.

12. In a furnace, means for supplying fluid fuel to the furnace, an outlet flue provided with a damper, a balanced draft device operated in accordance with variations in difference between atmospheric and furnace pressures for operating the flue damper, means for atomizing the fluid fuel, and a common means for controlling the rate of supply of atomizing fluid and adjusting the position of said balanced draft directly in response to variations in the rate of supply of fluid fuel to the furnace.

13. In a furnace, means for supplying fluid fuel to the furnace, an outlet flue provided with a damper, a balanced draft device operated in accordance with variations in difference between atmospheric and furnace pressures for operating the flue damper, means for atomizing the fluid fuel, and a common means for controlling the rate of supply of atomizing fluid and adjusting the position of said balanced draft device to maintain a fixed relation between the rate of supply of fluid fuel of the furnace and the rate of supply of air to the furnace.

EMBURY McLEAN.
